DESIGN.

G. P. HOLDEN.
BICYCLE SADDLE SPRING.

No. 28,513.

Patented Apr. 26, 1898.

UNITED STATES PATENT OFFICE.

GEORGE PARKER HOLDEN, OF KINGSTON, NEW YORK.

DESIGN FOR A BICYCLE-SADDLE SPRING.

SPECIFICATION forming part of Design No. 28,513, dated April 26, 1898.

Application filed November 13, 1897. Serial No. 658,496. Term of patent 7 years.

To all whom it may concern:

Be it known that I, GEORGE PARKER HOLDEN, a citizen of the United States, residing at Kingston, in the county of Ulster and State 5 of New York, have invented and produced a new and original Design for Bicycle-Saddle Springs, of which the following is a specification, reference being had to the accompanying drawings, forming part thereof.

Figure 1 is a plan view of a bicycle-saddle spring showing my new design. Fig. 2 is a section on the line $x-x$ and elevation of half of the saddle-spring, and Fig. 3 is a rearward perspective view in small size.

As shown in the drawings, the leading features of this design for a wire bicycle-saddle spring consist in the ovoidal spirals with the smaller convolutions downward and the end portions lying parallel or side by side, the wire at the upper parts of the convolutions being curved forward, bent double and

returned downward, and then bent double and continued forward as a base-loop. The configurations at opposite sides of the central vertical plane are similar, but reversed. 25

$a a'$ are the inclined ovoidal spirals, whose smaller convolutions extend downward and whose end portions $b b'$ lie parallel or side by side at the center line and whose upper parts curve and extend forward at $c c'$ and are 30 bent double at $d d'$ and inclined and then returned or continued backward and downward at $e e'$ and curved or bent double at $f f'$ and continued forward as a base-loop g .

What I claim is—

The design for a bicycle-saddle spring, substantially as shown and described.

GEO. PARKER HOLDEN.
